UNITED STATES PATENT OFFICE.

HENRY B. KEIPER, OF LANCASTER, PENNSYLVANIA.

INTERNAL-COMBUSTION ENGINE.

1,263,563.

Specification of Letters Patent. Patented Apr. 23, 1918.

Application filed May 29, 1913. Serial No. 770,665.

To all whom it may concern:

Be it known that I, HENRY B. KEIPER, a citizen of the United States, residing at Lancaster, in the county of Lancaster and State of Pennsylvania, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines, and more particularly to improved valve mechanisms for such engines and means for keeping the valves cool.

The primary object of the invention is to provide a simple, efficient, inexpensive and durable rotary valve for use with engines of the character referred to, adapted to operate quickly and noiselessly in opening and closing the inlet and exhaust ports, for admitting the explosive mixture to the working cylinder and allowing the exhaust gases and waste products of combustion to escape, and to prevent the accumulation of carbon on the valves and their seats and thereby prevent the disagreeable "knocking" sound and premature explosions which result from the deposit of carbon on the valves and valve seats and piston in the operation of internal combustion engines as heretofore constructed. Other objects are to provide an improved valve mechanism together with simple and efficient means for adjusting and sustaining the valves in proper position and for taking up any wear.

The invention will be first hereinafter more particularly described, with reference to the accompanying drawings, which are to be taken as a part of this specification, and then pointed out in the claims at the end of the description.

In said drawings:—

Figure 1 represents a plan view, partly in section, of an internal combustion engine embodying my invention;

Fig. 2 is a vertical sectional elevation of the same, a portion of the cylinder being broken away;

Fig. 3 is a vertical sectional elevation of the cylinder-head or valve-casing; the section being taken on the line 3—3 of Fig. 1;

Fig. 4 is a horizontal sectional view through the valve-casing showing a modified form of valve mechanism with the rollers in the position in which they are shown in Fig. 2;

Fig. 5 is a plan view illustrating the application of wearing rings to the valve, and

Figs. 6, 7 and 8 are detail cross-sections taken on line 6—6, 7—7 and 8—8, respectively of Fig. 5.

Referring to the drawings, in which the same reference letters are used to note corresponding parts in different views, the letter A may denote the cylinder of an internal combustion engine in which a reciprocating piston is employed and adapted to operate in the usual manner, said cylinder being provided with the usual water jacket or space for the circulation of water or other cooling medium, and B may denote the cylinder-head or valve-casing mounted thereon. To provide for the circulation of water or other cooling medium around the valves seated in said head or casing, the latter is provided with a water space extending around the valve at each end and in communication with the water jacket of the cylinder. The cylinder head or valve-casing B may be formed integrally with or secured upon the upper end of the cylinder by any suitable means, and is formed or provided with parallel intersecting bores, in which are seated a pair of rollers C, C, each having in its periphery a recess or cut-away portion c which extends transversely thereof, or at right angles to its axis, and is adapted to register with a corresponding recess in the periphery of the adjacent roller so as to provide an opening between the rollers when said recesses are directly opposite each other for the admission of the explosive mixture or charge to the cylinder through the inlet port D, and also a recess c¹ adapted to register with a corresponding recess in the other roller so as to provide an opening between the rollers in communication with the exhaust D¹ for the escape of

of the exhaust gases and waste products of combustion when the latter recesses are brought directly opposite each other, as they will be once during each revolution of the 5 rollers. As will be seen, the rollers C, C, are fitted in the parallel intersecting bores of the valve-casing and each may be provided at one end with a spur gear meshing with a similar gear on the end of the other 10 roller, so that when one roller is revolved it will impart motion to the other roller and cause the two to revolve in opposite directions. One of said rollers may also be provided with a reduced end portion or extension which projects through a stuffing 15 box in the cylinder head or valve-casing and is provided with a suitable gear wheel, such as a bevel gear E adapted to engage a similar gear wheel on a vertical shaft, 20 journaled in brackets projecting from the cylinder and geared to the crank shaft of the engine, so that motion will be imparted to the rotary valve for opening and closing the inlet and exhaust ports alternately once 25 during each revolution of the rollers constituting said valve. The rollers C, C, may be either solid or hollow, if desired, to permit the circulation of air or liquid therethrough in order to keep them cool; any 30 suitable pumping device being used to effect the desired circulation.

As will be seen, a water circulating space is provided around the working cylinder in communication with the water space which 35 surrounds the valve, so that water entering the cylinder at X will pass around the same and up into the water space of the valve-casing around the same and over the valves at each end of the casing and out at the exit 40 X', so as to prevent undue heating of the valves. For the purpose of lubricating the valves a socket is provided in the valve-casing for the attachment of an oil or grease cup, from which the lubricant will pass 45 through a duct e to the periphery of one of the rollers which is in contact with the periphery of the other roller so as to supply lubricant to the latter.

In Fig. 4 of the drawings I have shown 50 a modification in which the general construction and arrangement of parts is substantially the same as described with reference to Figs. 1 to 3, except that the valve seats provided by the intersecting bores are 55 slightly tapering in form and the rollers are correspondingly tapered in order that any wear which may result from long and continuous use may be taken up. To this end set screws F fitted in a yoke G press against 60 the ends of the rollers on which the intermeshing gears are fixed and coiled or other suitable springs H are interposed between the roller ends and yoke so as to exert sufficient pressure to hold the valves to their

seats and to automatically take up wear. 65 For the purpose of holding both rollers with the marginal portions of their registering recesses in exact alignment and to prevent endwise movement of either roller independently of the other, the gear on one roller 70 may have peripheral flanges thereon between which the periphery of the other roller is confined so that any pressure tending to force either roller endwise will be exerted simultaneously on both rollers. The 75 bracket or yoke G may also be provided with elongated slots to receive the fastening bolts g so as to permit a very nice adjustment of the rollers, to take up wear and the described connection between the ends of the 80 rollers permits such adjustment to be made without throwing the marginal portion of the registering recesses on the peripheries of the rollers out of alignment.

In Figs. 5 to 8 of the drawings I have 85 illustrated the application of wearing rings to the valve in which the rollers C, C, are provided with split rings e¹, e¹, at their ends constructed preferably of spring steel adapting them to be sprung over the ends of the 90 rollers into annular grooves in which they are retained, and with intermediate rings e², having flattened portions e³ to adapt them to conform to the shape of the recessed portions of the rollers such rings being split obliquely, as shown, to adapt them to be sprung over the ends of the rollers and slipped into their places, thus providing a wearing surface that may be renewed from time to time by substituting new rings for 100 those that are worn.

The operation of the invention will be readily understood from the foregoing description in connection with the accompanying drawings. In the position shown both 105 the inlet and exhaust ports are closed, the rollers being in the position they occupy while the piston is moving upwardly for compressing the charge. Both ports remain closed while the piston is making the 110 full upward stroke and a full downward or working stroke caused by the explosion which occurs at the end of the first upward stroke of the piston. The recesses which communicate with the inlet port or conduit 115 leading from the source of supply of the explosive mixture will be thrown into registering position or directly opposite each other, opening the inlet port for the admission of the explosive mixture immediately 120 after the exhaust port closes, and once during each revolution, while the registering recesses which communicate with the exhaust port will be brought into registering position or directly opposite each other also 125 during each revolution, but when the intake port closes a considerable interval of time elapses before the exhaust port is again

opened, thus allowing time for the piston to move upward and back for compressing a charge and effecting an explosion before the exhaust port opens for the discharge of the exhaust gases and waste products of combustion which are expelled on the next upward movement of the piston, and on the next downward movement thereof the inlet port opens for the admission of another charge.

It will be understood, of course, that various changes may be made in the details and arrangement of parts without departing from the spirit and scope of my invention.

15 Any suitable driving mechanism may be employed for imparting motion to the rotary valve either by means of a vertical driving shaft and gearing such as shown partly in full and dotted lines (Fig. 1) or a belt or 20 chain drive such as is well known in the art.

Having thus described my invention what I claim as new and desire to secure by Letters Patent is:—

1. In an internal combustion engine, a 25 rotary valve comprising a pair of rollers each having in its periphery a plurality of recesses, one recess of each roller being adapted to register with a corresponding recess of the other roller to open the inlet port once during each revolution of the rollers and then close the same, and other recesses of the two rollers being adapted to register and open the exhaust port when the inlet port is closed.

35 2. In an internal combustion engine, a rotary valve comprising two revolving rollers, each having a plurality of recesses in its periphery extending transversely of its axis, one recess being out of axial alignment with the other and the recesses of one roller adapted to register successively with corresponding recesses in the other roller and alternately open and close the inlet and exhaust ports once during each revolution.

45 3. In an internal combustion engine, a self-cleaning valve comprising a pair of rollers revolvably fitted in intersecting bores of a cylinder-head or valve-casing, each of said rollers having a plurality of recesses in its periphery, one arranged out of axial alignment with the other, the recesses of one roller being adapted to register successively with those of the other roller once during each revolution to alternately open and close the inlet and exhaust ports.

55 4. In an internal combustion engine, a valve-casing having intersecting bores to provide valve seats therein, and a valve comprising two oppositely rotating tapering rollers fitted in said bores and each having a plurality of recesses therein, the recesses of one roller being adapted to register successively with corresponding recesses in the periphery of the other roller for opening the

inlet and exhaust ports alternately as the 65 rollers revolve.

5. In combination, a valve-casing having intersecting bores to provide valve seats therein, and a valve comprising two oppositely rotating tapering rollers fitted in said bores and each having a plurality of recesses therein, the recesses of one roller being adapted to register successively with corresponding recesses in the periphery of the other roller for opening the inlet and exhaust ports alternately as the rollers 70 revolve, and means for adjusting said rollers endwise to take up wear.

6. In combination, a valve casing having intersecting bores to provide valve seats 80 therein, and a valve comprising two oppositely rotating tapering rollers fitted in said bores and each having a plurality of recesses therein, the recesses of one roller being adapted to register successively with corresponding recesses in the periphery of the other roller for opening the inlet and exhaust ports alternately as the rollers 85 revolve, and means arranged to exert a yielding pressure tending to force the rollers endwise to hold the registering recesses in alignment and automatically take up wear.

7. In an internal combustion engine a valve casing having intersecting bores, a valve comprising two oppositely rotating 95 rollers in peripheral contact seated in said bores and having registering recesses in their peripheries adapted to be brought successively into alignment with the inlet and exhaust ports to open said ports alternately 100 as the rollers revolve, and an oil duct leading to the periphery of one of said rollers for lubricating it and thereby lubricating the roller in peripheral contact therewith.

8. A rotary valve comprising two rollers 105 having recesses in their peripheries adapted to be brought into registering position or directly opposite each other to open the inlet and exhaust ports alternately as the rollers revolve; the ends of the rollers having 110 split wearing rings sprung into annular recesses therein and the intermediate portions thereof having split rings sprung thereon the latter rings having flattened portions fitting the recesses in the peripheries 115 of the rollers.

9. In combination with a valve casing having intersecting bores, a rotary valve comprising a pair of rollers seated in said bores, each roller having a plurality of recesses in its periphery arranged out of axial alignment and adapted to register successively with corresponding recesses in the adjacent roller, gearing for rotating said rollers in opposite directions, and means for 120 moving said rollers endwise in unison.

10. In an internal combustion engine, a rotary valve comprising a pair of revoluble

rollers each having a plurality of recesses in its periphery arranged out of axial alignment, the recesses of one roller being adapted to register successively with correspondingly arranged recesses in the other roller to open and close alternately the intake and exhaust ports; said recesses being positioned on the peripheries of the rollers so that a considerable interval of time elapses between the

closing of the intake port and the opening of the exhaust port.

In testimony whereof I affix my signature in the presence of two witnesses.
